UNITED STATES PATENT OFFICE.

EMIL GEORGE HESS AND WILLIAM HESS, OF WEST TORONTO JUNCTION,
CANADA, ASSIGNORS TO ALICE GRACE HESS, OF SAME PLACE.

DESIGN FOR A KNOB OR PULL.

SPECIFICATION forming part of Design No. 21,197, dated December 1, 1891.

Application filed January 22, 1891. Serial No. 378,704. Term of patent 14 years.

To all whom it may concern:

Be it known that we, EMIL GEORGE HESS and WILLIAM HESS, both of the town of West Toronto Junction, in the county of York, in the Province of Ontario, Canada, have invented and produced a new and original Design for Knobs or Pulls, of which the following is a specification.

Figure 1 is a face view of the knob embodying our design, and Fig. 2 is a perspective view.

The leading features of our design consist in the fluting of the knob or pull from the

inner end or ring A, behind the inner end of the knob, to the outer face of the knob, where the flutes form petal-shaped offsets b, radiating from the center or stamen B on the outer face on a line with the axis of the knob.

What we claim is—

The design for a knob or pull herein shown and described.

EMIL GEORGE HESS.
WILLIAM HESS.
